UNITED STATES PATENT OFFICE.

EARL J. BRACKEN, OF BUTTE, MONTANA.

AUTOMOBILE WINDOW SCREEN.

Application filed December 7, 1923. Serial No. 679,165.

To all whom it may concern:

Be it known that I, EARL J. BRACKEN, a citizen of the United States, residing at Butte, in the county of Silverbow, State of Montana, have invented certain new and useful Improvements in Automobile Window Screens; and I do hereby declare the following to be a full, clear, and exact description of the invention, such as will enable others skilled in the art to which it appertains to make and use the same.

This invention relates to window screens, and particularly to screens which are especially adapted for use in the sedan type of automobiles.

One object of the invention is to provide a screen of this character which is simple and neat in its construction, and which is adapted to be fitted into the grooves ordinarily occupied by the sliding glass panel of the automobile.

Another object is to provide a screen of this character which is so formed that the glass panel aids in holding the screen within the window opening.

A further object is to provide a screen of this character which can be easily handled when applying or removing the same, and which is strong and durable in its construction and use.

A still further object is to provide a screen which is particularly adapted to the front window opening, to permit the driver to extend his hand, when signaling for a change of direction, and which will normally close.

Other objects and advantages will be apparent from the following description when taken in connection with the accompanying drawing.

40 In the drawing:

Figure 1 is an elevation of a portion of the body of an automobile of the sedan type, showing the screen in position, and in connection with a vertically slidable glass panel.

Figure 2 is an enlarged vertical sectional view on the line 2-2 of Figure 1.

Figure 3 is a horizontal, enlarged, sectional view on the line 3-3 of Figure 1, the movable sections being shown in open position, in dotted lines.

Figure 4 is a fragmentary elevation, partly broken away, showing the spring urged strips of the screen frame.

55 Referring particularly to the accompanying drawing, 10 represents a portion of the

body of an automobile, having the door 11 provided with the window opening 12. In each of the vertical side walls of the window opening 12 there is formed a longitudinal 60 groove 13, within which the side edge portions of the glass panel 14 are arranged to slide. A similar groove 15 is formed in the transverse upper wall of the opening 12, which receives the upper edge portion of the 65 glass panel, when said panel is raised into closed position.

The screen, forming the subject-matter of the present application, includes a frame, having the vertical side members 16 and 17, 70 and the upper and lower members 18 and 19. In the outer face of each of the members 16 and 17 there is formed a longitudinal groove 20, which receives the longitudinal edge portion of the metal or other rigid strip 21. 75 Also formed in the said face of each side member, are the circular recesses 22, and in each recess there is seated a coil spring 23, the outer end of which bears against the said edge of the strip 21, to urge the same outwardly, into the groove of the window opening. Each strip 21 is formed with a plurality of openings 24, and disposed through the members 16 and 17, and through the openings, are retaining pins 25, which limit 80 the outward movement of the strips, under the pressure of the springs. The outer edge portions of the strips 21 are arranged to be seated within the grooves 13, of the window opening, and to be held firmly in such position by the pressure of the springs 23.

Fixed within a groove 26, in the upper member 18, of the screen frame, is a strip 27, similar to the strips 21, but immovable, said strip 27 being arranged to engage in the 95 groove in the upper wall of the window opening. The lower face of the lower member 19, of the frame, is formed with a comparatively wide double beveled groove or channel 28, for the reception of the upper 100 edge portion of the glass panel 14, whereby, when said panel is raised, by means of the usual mechanism, the screen frame will be pushed upwardly until the strip 27 seats itself within the groove 15. A sheet of suitable fine screen fabric 29 is secured within the upper portion of the screen frame, the lower marginal edge of which is retained by the transverse strip 30, which has its ends secured to the side members 16 and 17, of 110 the frame.

Secured to the vertical side member 16 of

- the screen frame, adjacent the transverse strip 30, and adjacent the lower member 19, are the horizontally extending flexible strips 31, the same extending to approximately the center of the lower portion of the frame, and being connected by the vertical end strip 32. Secured to the strips 31 and 32 is a sheet of wire fabric 33, vertical and diagonal braces 34, and 35, being secured to the strips to form a rigid structure. Secured to the side member 17, and arranged at points corresponding to those at which the strips 31 are secured, are similar flexible strips 36, their outer ends, which are disposed in close proximity to the free ends of the strips 31, being connected by a vertical strip 37.
- There are thus provided two small swingable frames, which may be easily pushed into open position by the hand of the driver, when he desires to signal to other vehicles of a change of direction. The strips 31 and 36 being flexible, readily permit the small frames to be easily swung open, and upon being released will swing into closed position. The other small frame, which consists of the strips 36 and 37 is covered with screen fabric 38, so that when the small frames or doors are in closed position they close the lower portion of the main screen frame.
- When the screen device is properly seated within the window opening, and the glass panel elevated to engage the frame and push the same upwardly, the entrance of insects, dust, and the like, is effectively prevented,

and riding in this type of automobile rendered comfortable. 35

The screen is also adapted for use in the other window openings of the automobile, and in this case the swinging doors are omitted, the screen fabric extending across 40 the entire screen frame.

What is claimed is:

1. The combination with the window opening of an automobile, of a screen frame fitted within said opening and having a stationary upper screen fabric covered portion, horizontally swingable screen fabric covered doors having flexible frames mounted in the lower portion of the screen frame and normally and flexibly retained in closed position, said doors being capable of being pushed open by the hand of the driver for the purpose of signaling. 45
2. A screen for the window opening of an automobile comprising a frame, screen fabric covering the upper portion of the frame, and doors mounted in the lower portion of the frame, and each including a screen fabric covered frame having upper and lower flexible bars having their corresponding ends secured to the first frame. 55

In testimony whereof, I affix my signature, in the presence of two witnesses.

EARL J. BRACKEN.

Witnesses:

FRED V. ARMFIELD,
THOMAS M. MULVANEY.
